UNITED STATES PATENT OFFICE

HAROLD G. WARR, OF PARK RIDGE, ILLINOIS, ASSIGNOR TO MAINTENANCE EQUIPMENT COMPANY, OF CHICAGO, ILLINOIS, A CORPORATION OF ILLINOIS

WHEEL FLANGE OILER

Application filed October 11, 1928. Serial No. 311,874.

This invention relates to certain new and useful improvements in wheel flange oilers, and more particularly to improved means for distributing and spreading the oil on 5 the car wheel flange.

Numerous devices have been designed and used for projecting or pumping oil from a reservoir against a portion of the rail head, or against the flange of a passing car wheel. 10 Usually this oil is discharged in a single stream against a localized portion of the rail head or wheel flange, much of the oil being lost, and the oil being very poorly distributed on the wheel flange. According to 15 15 the present invention, a distributing plate is secured along the inner side of the rail, this plate being of considerable length and having a tapered flange which fits along one side of the rail head so as to have a considerable 20 area engaging the inner surface of the car wheel flange to act as a spreading means for the oil. A plurality of oil conduits is formed in this tapered flange of the distributing plate so that oil may be simultaneously 25 charged from a plurality of spaced outlets in this plate and thus taken up by the wheel flange and spread along the entire circumferential surface of the wheel flange by the continuous wiping engagement of this 30 surface with the distributing plate.

The principal object of this invention is to provide, in a wheel flange oiling system, an improved distributing means, such as briefly described hereinabove and such as 35 disclosed in detail in the specifications which follow.

Other objects and advantages of this invention will be more apparent from the following detailed description of one approved 40 form of the apparatus.

In the accompanying drawings:

Fig. 1 is a transverse vertical section through one form of oiling system and the 45 improved distributing plate, as applied to a standard rail.

Fig. 2 is a partial vertical section, taken substantially on the line 2-2 of Fig. 1.

Fig. 3 is a perspective view, on a smaller 50 scale, showing the distributing plate attached in operative position on the rail.

The means shown here by way of example for pumping the oil from the reservoir will first be described briefly, it being understood that any other approved means for feeding the oil could be utilized. At one side of the rail head 1, a lever or treadle 2, here shown in the form of a channel bar, is so mounted that it will be depressed by the tread of a passing car wheel, indicated in dotted lines at 3. The channel bar 2 will be normally held in the position shown in solid lines in 55 Figs. 1 and 2, and will be returned to this position after being depressed by the car wheel, by suitable spring supporting means, not here illustrated.

Intermediate the ends of the bar 2 are pivotally mounted at 4 and 5 a pair of links 6 and 7 formed with integral rack segments 8 and 9, respectively. The teeth of the rack segments 8 and 9 project in opposite directions and mesh with the opposite sides of a ratchet wheel 10 mounted on a shaft 11 journaled at one end in a housing 12 secured by bolts 13 to the rail 1. The pivoted links 6 and 7 are resiliently urged toward the ratchet 60 wheel 10 by means of springs 14 and 15 carried by the housing 12. It will be noted that on the downward movement of the bar or lever 2, the ratchet 10 will be given a partial rotation in the direction of the arrow by means of 65 the rack 9, the spring 14 yielding to permit the rack 8 to slip freely over the ratchet. When the lever or bar 2 returns to its elevated position, the teeth of rack 8 will engage the ratchet wheel 10 to cause a further movement in the direction of the arrow, the spring 70 75 80 85 90 95 100 14 yielding at this time to permit the rack 9 to slip freely over the ratchet teeth. In this manner the ratchet wheel 10 will be intermittently rotated in one direction by the up and down movements of the actuating bar 2.

Secured to opposite sides of the ratchet wheel 10 are friction rings 16 and 17 formed of leather, fibre or other suitable friction material. These rings bear respectively against rings 18 and 19 which are suitably keyed to the shaft 11. A helical spring 20 abuts at one end against the adjusting nut 21 threaded on shaft 11 and serves to yieldingly clamp the 100

ratchet wheel 10 between the friction rings 18 and 19.

Shaft 11 is connected by coupling 22 with the actuating shaft 23 of a pumping mechanism 24 mounted within a lubricant container or reservoir 25. The reservoir 25 is supported upon a plate 26 connected to the base flanges of rail 1 by means of clamps 27 and 28 connected by bolts 29. The receptacle 10 or reservoir 25 is preferably cylindrical in shape and has a disc plunger 30 slideable therein, this plunger being depressed by atmospheric pressure admitted through aperture 31 in the removable cover plate 32. The 15 pumping mechanism 24 may be of any suitable form and is not disclosed in detail. A pipe or oil conduit 33 leads from the pump 24 beneath the rail 1 to the distributing plate which forms the particular subject matter of 20 this invention.

It will be understood that each time a wheel 3 passes along the rail 1, the lever or treadle bar 2 will be depressed and subsequently elevated, these movements causing an intermittent rotation of the shafts 11 and 23, the pumping mechanism 24 thus being actuated to force oil from reservoir 25 through the discharge pipe 33 to the distributing plate, hereinafter described. The specific oil pumping mechanism briefly described hereinabove is not herein claimed, but is disclosed more in detail and claimed in the copending application of Bates, Serial No. 301,741, filed Aug. 24, 1928. It is to be understood that any 35 other suitable form of mechanism might be utilized for forcing oil from a reservoir to the distributing plate, the above described mechanism being merely disclosed here by way of example.

40 It has been found that if oil is discharged from the pipe 33, through any suitable outlet, directly against the head of the rail 1 or the inner surface of rail flange 34, by any pumping or projecting mechanism, such as 45 just described by way of example, the oil will impact against the rail head or wheel flange with considerable force so that a great deal of it will be spattered away and lost, and the surfaces oiled on the rail head or 50 flange will be quite localized. The particular object of the present invention is to provide a means for securing a better distribution of the oil along the wheel flange, and avoiding the excessive loss of oil.

55 The distributing plate 35 has a portion shaped to fit between the head and flange of the rail, and is secured to the web of the rail by bolts 45 in a well known manner. The plate 35 has an upwardly tapering flange 36 60 designed to lie closely along the side of the rail head, with its outer surface substantially conforming to the inner surface of the wheel flange 34, so that as the wheel flange passes along the rail, it will contact continuously 65 with a considerable area of the flange 36. A

70 plurality of oil outlets 37 are positioned at spaced intervals in the flange 36, as closely adjacent the crown of the rail 1 as is practicable. Oil conduits 38, suitably formed within the body of the plate 35, lead from the outlets 37 to a common inlet 39 with which the pipe 33 leading from the pumping mechanism 24 is connected. Shallow recesses 40 are formed in flange 36 about the discharge outlets 37 so that the wear or pounding to which 75 the plate is subjected will not close the oil outlets.

80 It will be apparent that the oil forced through conduit 33 will be discharged through the plurality of outlets 37 onto the outer surface of flange 36 or directly against the inner surface of a wheel flange 34 if said flange is passing over the outlet. Since the stream of oil projected through pipe 33 is 85 divided between the several outlet conduits 38, its impetus will be so diminished that it will not be discharged from outlets 37 with any excessive force and will merely run out onto the outer surface of flange 36, where it 90 will be picked up by the inner surface of flange 34 and spread continuously along the inner surface of this flange, due to the continuous rubbing or wiping contact between the flange and the distributing flange 36. It 95 is to be understood that the plate 35 may be made of considerable length, and the number of outlets 37 increased in accordance with the discharging capacity of the oil pumping system. The number of outlets should be so proportioned to the pumping system that the oil 100 will be ejected from all of the outlets, but not with excessive force, so that it may be properly distributed by the engaging flanges 36 and 34 as described hereinabove.

105 I claim:

110 1. In a wheel flange oiling system, a distributing plate comprising a portion adapted to be secured to the rail and a tapered flange adapted to lie alongside the railhead and engage the inner surface of a wheel-flange with a wiping action to distribute the oil on the wheel flange, there being an oil conduit formed in said plate, the outlet of the conduit being in the outer wheel-flange engaging face of the tapered flange adjacent the crown 115 of the railhead.

120 2. In a wheel flange oiling system, a distributing plate comprising a portion adapted to be secured to the rail and a tapered flange adapted to lie alongside the railhead and engage the inner surface of a wheel-flange with a wiping action to distribute the oil on the wheel flange, there being a plurality of oil conduits formed in the plate, the outlets of these conduits being located at longitudinally spaced intervals in the outer wheel-flange 125 engaging face of the flange portion of the distributing plate.

130 3. In a wheel flange oiling system, a distributing plate comprising a portion adapted

to be secured to the rail and a tapered flange adapted to lie alongside the railhead and engage the inner surface of a wheel-flange with a wiping action to distribute the oil on the wheel flange, there being an oil inlet formed in the lower portion of the plate and a plurality of oil conduits leading from this inlet to outlets located at longitudinally spaced intervals in the outer wheel-flange engaging face of the flange of the distributing plate.

4. In combination with an oil reservoir positioned adjacent a rail and a pumping system for discharging oil from the reservoir, said pumping system comprising actuating means that is depressed by a car wheel passing along the rail, a distributing plate comprising a portion adapted to be secured to one side of the rail and a tapered flange adapted to lie alongside the railhead and engage the inner surface of a wheel flange with a wiping action to distribute the oil on the wheel-flange, there being an oil conduit formed in the plate, the outlet of the conduit being in the outer wheel-flange engaging face of the tapered flange adjacent the crown of the railhead, and a pipe connection leading from the pumping system to the inlet of the conduit.

5. In combination with an oil reservoir positioned adjacent a rail and a pumping system for discharging oil from the reservoir, said pumping system comprising actuating means that is depressed by a car wheel passing along the rail, a distributing plate comprising a portion adapted to be secured to one side of the rail and a tapered flange adapted to lie alongside the railhead and engage the inner surface of a wheel flange with a wiping action to distribute the oil on the wheel-flange, there being a plurality of oil conduits formed in the plate, the outlets of these conduits being located at longitudinally spaced intervals in the outer wheel-flange engaging face of the flange portion of the distributing plate, and means for conducting oil from the pumping system to the inlets of the several conduits.

6. In combination with an oil reservoir positioned adjacent a rail and a pumping system for discharging oil from the reservoir, said pumping system comprising actuating means that is depressed by a car wheel passing along the rail, a distributing plate comprising a portion adapted to be secured to one side of the rail and a tapered flange adapted to lie alongside the railhead and engage the inner surface of a wheel flange with a wiping action to distribute the oil on the wheel-flange, there being an oil inlet formed in the lower portion of the plate and a plurality of oil conduits leading from this inlet to outlets located at longitudinally spaced intervals in the outer wheel-flange engaging face of the flange of the distributing plate,

and a pipe connection leading from the pumping system to the oil inlet.

7. In a wheel flange oiling system, a distributing plate adapted to be mounted at one side of the rail-head so as to extend longitudinally of the rail, said plate tapering upwardly and inwardly toward the rail so as to substantially fit between the rail-head and inner surface of the wheel flange and serve as a wiping means to distribute the oil on the flange, there being an oil conduit formed in the plate for delivering oil through the outer wheel-flange engaging face of the tapered plate to the surface of a wheel flange.

8. In a wheel flange oiling system, a distributing plate adapted to be mounted at one side of the rail-head so as to extend longitudinally of the rail, said plate tapering upwardly and inwardly toward the rail so as to substantially fit between the rail-head and inner surface of the wheel flange and serve as a wiping means to distribute the oil on the flange, there being an oil conduit formed in the plate and terminating in a plurality of outlets positioned in the outer wheel-flange engaging face of the tapered plate and spaced longitudinally of the rail for delivering oil to the surface of a wheel flange.

9. In a wheel flange oiling system, a distributing plate adapted to extend longitudinally of a rail and comprising a supporting portion adapted to fit between the rail-head and the base flange of the rail, and an upwardly tapering portion adapted to fit alongside the rail-head and extend between the rail-head and the flange of a car wheel and serve as a wiping means to distribute the oil on the flange, and means for distributing oil through outer wheel flange engaging face of the tapering portion of the plate to the wheel flange.

10. In a wheel flange oiling system, a distributing plate adapted to extend longitudinally of a rail and comprising a supporting portion adapted to fit between the rail-head and the base flange of the rail, and an upwardly tapering portion adapted to fit alongside the rail-head and extend between the rail-head and the flange of a car wheel and serve as a wiping means to distribute the oil on the flange, there being oil conduits formed in the plate and extending from an inlet in the supporting portion to a plurality of outlets spaced at longitudinal intervals in the outer wheel-flange engaging face of the tapered portion so as to direct the oil against the wheel flange.
